UNITED STATES PATENT OFFICE.

MAYME JEFFERSON PEPPARD, OF MINNEAPOLIS, MINNESOTA.

HAIR-CURLER.

1,217,816.

Specification of Letters Patent. Patented Feb. 27, 1917.

Application filed October 26, 1914. Serial No. 868,620.

To all whom it may concern:

Be it known that I, MAYME JEFFERSON PEPPARD, a citizen of the United States, residing at Minneapolis, in the county of Hennepin and State of Minnesota, have invented a new and useful Improvement in Hair-Curlers, of which the following is a specification.

This invention relates to an improvement 10 in hair curlers, the primary object being to provide a simple and inexpensive device, which is free from angles and crevices to catch or in any way injure the hair. A further object is the production of a device for 15 curling and waving hair, which has a feeling of smoothness to the user, and which will most effectively hold the convolutions of hair tightly together, so that the hair is most effectively curled or formed in waves. 20 These and other objects will be apparent from the following description.

To these ends my invention comprises the features of construction and combination of parts hereinafter more particularly described and claimed.

In the accompanying drawing forming part of this specification, Figure 1 is a plan of my invention, and Fig. 2 is another plan view when the elastic band is secured in 30 place after the hair has been wound upon the curler.

In constructing my invention, it is preferable to make the frame of the device from a single piece of aluminum wire, this material producing a non-corrodible curler, which has a smooth feeling and which is not too slippery for holding the hair tightly, after it has been wound upon the device. A piece of this material is cut in 40 suitable length and is shaped with a crotch A on one end, an eye B on its opposite end, and a pair of curved bars C and D forming a shank extending from the sides of the crotch to the eye. More in detail the crotch is shaped with an inwardly bent portion 3 forming a recess having sides 4 and 5 inclined inwardly toward an apex. These inwardly tapering sides act as guides for most effectively directing the elastic ring or band 50 E into the recess of the crotch, said band being secured through the eye B, and adapted to be stretched lengthwise over the curler and thus held by said crotch. The outer portions of the sides 4 and 5 are curved back 55 and merge into side bars C and D, which are curved inwardly lengthwise until meet-

ing at a point immediately adjacent the eye B. At the point of merging referred to, the joint 6 between the ends of the piece of wire and the sides C and D are secured together by means of a clip in the form of a double ferrule 7 made out of thin sheet metal tightly clasped about the bars C and D, and over the joint 6. In this manner the eye B is completed and sealed, and is adapted to hold the band of elastic material from becoming detached from the device. In view of the band of elastic material passing through the eye in the manner stated, the ring is adapted to span the curler and hold the convolutions of hair on both sides of the device when the ring is stretched and secured in the crotch. The inwardly curved sides which merge together at the end of the device adjacent the eye tend to 70 pack the convolutions of hair tightly together toward the eye end of the curler, causing the convolutions when so packed and held by the elastic band E to eventually curl or form the hair in waves most effectively. The crotch formation also acts as a handle for the device, enabling the device to be held and manipulated by hand during the operation of curling the hair. The recess is also sufficiently deep in the crotch to serve 85 in engaging the elastic band and prevent it from slipping off of the end of the curler when it is in stretched condition. The band E is of continuous length and is secured in the eye by passing its side singly therethrough before the eye is sealed by the clip. In this manner a bulky projection such as is produced in prior devices where the band is doubled about the end of the curler is avoided, which is an advantage. 95

In accordance with the patent statutes I have described the principles of operation of my invention, together with the apparatus which I now consider to represent the best embodiment thereof, but I desire to have 100 it understood that the construction shown is only illustrative and that the invention can be carried out by other means and applied to uses other than those above set forth within the scope of the following claim. 105

Having described my invention, what I claim as new and desire to protect by Letters Patent is:—

A hair curler comprising a single piece of wire formed with an inwardly projecting 110 crotch on one end having its recess formed by inwardly converging sides producing

guide members for directing purposes, the outer end portions of said crotch being bent backwardly and inwardly to form side portions meeting adjacent their ends, one of 5 said portions being longer than the other and bent backwardly to form an eye, the end thereof being adjacent the end of the other portion, a fastener surrounding the meeting portions of said sides for holding 10 them together and an elastic band through which the eye portion of said wire passes and

wherein it is retained by said fastener, said band being adapted for engagement within said crotch when stretched longitudinally over the device.

15

In testimony whereof, I have signed my name to this specification, in the presence of two subscribing witnesses.

MAYME JEFFERSON PEPPARD.
